UNITED STATES PATENT OFFICE

MILON H. BORZIN, OF CHICAGO, ILLINOIS

CONTAINER

Application filed March 19, 1928. Serial No. 262,958.

The present invention relates to an improvement in permutation locks, and has for its object to provide a lock adapted for use with containers, safes and the like and which may be operated with facility by one knowing the combination of the same.

A still further very important object of the invention resides in the provision of a lock of this nature which is comparatively simple in its construction, inexpensive in its manufacture, strong and durable, thoroughly efficient and reliable, and otherwise well adapted to the purpose for which it is designed.

A still further very important object of the invention resides in the provision of a novel safe having its peculiarly formed compartment for the permutation locked parts and having a novel lid for being locked by said permutation lock.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of a safe embodying the features of my invention,

Figure 2 is a vertical longitudinal section therethrough,

Figure 3 is a vertical transverse section therethrough taken substantially on the line 3-3 of Figure 2,

Figure 4 is a front end elevation thereof,

Figure 5 is a perspective view showing the cover fragmentarily and in open position;

Figure 6 is a bottom plan view of the cover,

Figure 7 is a disassembled view of the tumbler disk,

Figure 8 is a plan view of one of the washers, and

Figure 9 is an elevation of the spring.

Referring to the drawing in detail, it will be seen that the safe illustrated herein is in the form of a container having a bottom 5, side walls 6 arising therefrom, a rear end wall 7 rising therefrom provided on its upper edge at its center with an inwardly directed ear 8 having a headed pin 9 rising therefrom. A front wall 10 rises from the front end of the bottom 5 and is formed with an inward extension 11 at its upper end in parallelism with the bottom 5 and in turn merging into a downwardly extending partition 12 disposed in parallelism with the front wall 10. This partition 12 is formed with an opening 14 adjacent its upper end.

A cover 15 is provided on one end upon its bottom surface with a plate 16 having an elongated longitudinal slot 17 for receiving the pin 9 as is clearly indicated in Figure 2 so that the lid may be slid rearwardly and then swung outwardly to an open position as is indicated to advantage in Figure 5. The free end of this cover or lid 15 is provided with a bolt 18 projecting therefrom and provided with three transverse notches 19.

A shaft 20 is journaled through an opening in the front wall 10 and has a knob 21 on its outer forward end, said knob being provided with a flange 22 with suitable combination indicating indicia thereon. A sleeve 23 is fixed in an opening provided in the partition 12 and extends forwardly to terminate in spaced relation to the wall 10 and on said forward end is provided with an outwardly directed annular flange 24. A tumbler disk 25 is fixed to the shaft 20 and has a rearwardly extending projection 26 on its rear face as indicated at 20.

A tumbler disk 27 is rotatable on the sleeve 26 and has a forwardly extending projection 28 on its forward face and a rearwardly directed projection 29 on its 29

rear face. A tumbler disk 30 is provided with a forwardly directed projection 31. All of these projections are equally spaced from the common axis of the tumbler disk.

5 All the tumbler disks are provided with peripheral notches 32 through which the bolt 18 extends when being inserted through the opening 14 or withdrawn therefrom.

The disks are arranged so that their peripheries are rotatable in the notches 19 of the bolt 18 when the bolt 18 is locked. A washer 33 is disposed between disks 27 and 30. A spring 34 is disposed about the sleeve 23 and impinges against the disk 30 and the partition 12.

10 When the bolt 18 is in a locked position that is when one or more of the peripheries of the disk have portions disposed in the notches 19 it will be seen that by rotating the knob 21 in one direction the projection 26 will pick up the projection 28 and rotate the disk 27 so that the projection 29 will pick up the projection 31 and thus by one knowing the combination the disk 30 may be 15 located with notch in registration with the opening 14. Then the knob 21 may be rotated in the opposite direction until the projection 26 again picks up the projection 28 so that the disk 27 may be left with its 20 notch in registration with the opening 14 and then the knob 21 may be rotated in said 25 one direction to place the disk 25 with its notch in registration with the opening 14.

30 When the tumbler disks are thus positioned the cover 15 may be slid rearwardly by the pin and slot connection 9, 17 and then the lid may be swung out to one side.

35 It is thought that the construction, operation and utility and advantages of this invention will now be quite apparent to those skilled in this art without a more detailed description thereof.

40 The present embodiment of the invention has been disclosed in detail merely by way 45 of example since in actual practice it attains the features of advantage enumerated as desirable in the statement of the invention and the above description. It will be apparent that changes in the details of construction, 50 and in the combination and arrangement of parts may be resorted to without departing from the spirit or scope of the invention as hereinafter claimed or sacrificing any of its advantages.

55 Having thus described my invention, what I claim as new is:

60 A container of the class described comprising a bottom, side walls rising from the bottom, a rear wall rising from the bottom and having an inwardly directed ear at its upper edge parallel with the bottom, a pin rising from said ear, a front wall rising from the bottom and having an inwardly and rearwardly directed wall extension 65 parallel with the bottom and merging into

a downwardly extending partition in parallelism with the front wall and being provided with an opening, said front wall, extension and partition forming a compartment for a lock, a cover having a plate extension under one end thereof, said plate extension being provided with a slot to receive the pin, and a bolt at the other end of the cover projecting therefrom to be disposed through the opening in the partition.
